UNITED STATES PATENT OFFICE.

HARVEY JAMES DE FOREST, OF TURNER, MAINE, ASSIGNOR TO DE FOREST PRODUCTS COMPANY, OF TURNER, MAINE, A CORPORATION OF MAINE.

FABRIC HOLDER.

Application filed February 26, 1924. Serial No. 695,356.

To all whom it may concern:

Be it known that I, HARVEY J. DE FOREST, a citizen of the United States, and resident of Turner, in the county of Androscoggin and State of Maine, have invented certain new and useful Improvements in Fabric Holders, of which the following is a specification.

My present invention relates to a frame 10 for holding an area of fabric while certain work is being performed thereon.

The principal object of the invention is the provision of such means whereby an area of fabric of any desired kind may be 15 stretched to the required looseness or tightness while work is performed thereon, such as sewing, embroidering, or the working of a design upon the fabric by any desired method.

20 Specifically the invention has been found to be of great value in the producing of rugs made according to the method of my Patent No. 1,487,318.

Another important object of the invention 25 is the provision of means, as above, to which the fabric may be readily and quickly attached, and from which it may be detached.

Still another object is the arranging of 30 parts so that any portion of the fabric may be tightened or loosened without affecting the remainder.

To this end my invention includes a frame 35 adapted to either be supported in spaced relation from the floor, a table, or the like, or to be hung from a wall or ceiling, as may be desired. Around the periphery of the frame are provided hooks or fastening means adapted to engage a toothed comb 40 which directly engages the fabric. The hooks so cooperate with the comb that a pull on the comb by the fabric towards the center of the frame, causes the hooks to lock in the frame, which holds the fabric 45 stretched efficiently.

I have shown one embodiment of the invention in the accompanying drawings, which are to be taken as illustrating the preferred form only.

50 In these drawings:—

Figure 1 is a plan view of one form of the device, partly in section.

Fig. 2 is a side elevation of the device of Fig. 1.

Figs. 3, 4, 5 and 6, are details of the holding means.

Referring now more particularly to the illustration, the frame is shown at 1, supported upon legs 2. On the inside of the frame parts 1 are sockets or guide ways 3 having longitudinal deformations 4 slightly larger than the dimensions of a hook having a turned-over end 5 and a straight shank 6. The longitudinal deformation 4 is provided with a lateral cut, as shown at 7, the metal of the upper portion of the deformation 4 being punched or pressed in, as at 8, which is adapted to engage a cut away portion 9 in the shank 6 when the hook is pulled toward the center of the frame. That is, as long as the shank 6 of the hook lies substantially adjacent to the inner side of the frame parts, the pressed-in portion 8 does not engage the cut away portion 9 of the hook, but when pressure is exerted on the hooked end 5 toward the center of the frame, the pressed-in part 8 enters the cut away portion 9, which effectively prevents the hook from being withdrawn from the longitudinal deformation. A plurality of these hooks are located on the inside of the frame parts 1.

55 A comb member 10, substantially egg-shaped in cross section, is provided with teeth 11 along one edge, which teeth are adapted to engage the fabric shown at 12. It will be readily seen that when the comb 10 is placed beneath the hooked ends 5 of the fastening members, the fabric, if secured to the other side of the frame in the same manner, will tend to cause movement of the comb toward the other side of the frame. As above described, this causes the hooks to lock in their sockets. It will also be apparent that if the fabric passes between the top of the frame and the bottom of the comb 10, there is a tendency for the comb to rotate, which rotation ceases when the teeth 11 engage the top of the frame 1. It will also be seen that this partial rotation of the comb 10 about the under side of the comb adjacent the teeth as a fulcrum, causes upward movement of the rear top surface of the comb. This small amount of movement forces the hooks out of their 60 sockets until the pressed-in portion 8 engages the hook, as before mentioned, which securely retains comb and hook in locked

position. A similar comb is provided for each side of the frame.

When it is desired to tighten certain portions of the fabric without affecting the other parts, it is only necessary to take hold of that part of the fabric projecting beyond the frame at the point which it is desired to tighten, and pull slightly in a horizontal plane, which will release the fabric from the teeth at this point. Further pull will tighten the fabric, and upon moving this portion upwardly above the top of the comb, the teeth will be made to engage the fabric at a new point, and securely hold the fabric in this tightened position.

Having thus described my invention, what I claim is:—

1. A device of the character described, including a frame, a comb carried thereby, means for securing the comb to the frame, said comb being egg-shaped in cross section whereby the comb is wedged against the comb securing means by the partial rotation of the comb.

2. A device of the character described, including a frame, a comb carried thereby, means for securing the comb to the frame, said means including a hook, said hook being removably held in a socket carried by the frame, said socket including a member having a longitudinal deformation adapted to engage the hook and hold the same in position.

3. A device of the character described, including a frame, a comb carried thereby, means for securing the comb to the frame,

said means including a hook, said hook being removably held in a socket carried by the frame, said socket having a punched-in portion engaging said hook and retaining the same in the socket. 40

4. A device of the character described, including a frame, a comb carried thereby, means for securing the comb to the frame, 45 including a hook detachably socketed to the frame, said hook having a straight shank partially cut away, said socket having a punched-in portion adapted to engage the shank of the hook upon movement of the hook upward and toward the center of the frame. 50

5. In combination, a frame, a fabric stretched thereover, a comb placed on top of the fabric, teeth on the outside longitudinal edge of the comb, said teeth engaging the fabric, and means to secure the comb to the frame, the tension of said fabric causing said teeth to be depressed against said frame whereby the fabric is retained 60 in its stretched condition on the frame. 55

6. In combination, a frame, a fabric stretched thereover, a comb placed on top of the fabric, teeth on the outside longitudinal edge of the comb, said teeth engaging the fabric, means to secure the comb to the frame, tension of the fabric on one side of the frame causing the retention of the fabric on the comb, and a wedging action between the comb and its securing means on the other side of the frame. 65 70

In testimony whereof, I affix my signature.

HARVEY JAMES DE FOREST.
